UNITED STATES PATENT OFFICE

JOHN H. ASHBAUGH, OF PITTSBURGH, PENNSYLVANIA, ASSIGNOR TO WESTINGHOUSE ELECTRIC & MANUFACTURING COMPANY, A CORPORATION OF PENNSYLVANIA

REGULATOR SYSTEM

Application filed December 6, 1927. Serial No. 238,048.

My invention relates to a regulator of the carbon-pile type in which a series of current conducting wafers are used as a rheostat, the resistance value of the pile being varied by varying the pressure on the series of wafers.

Many regulators of this general type have been used to control the field current of a dynamo electric machine, for regulating the speed of a motor or the voltage of a generator. In this type of regulator, carbon or graphite disc wafers are connected in series with the shunt field winding of the machine to be regulated, and the pressure on the pile of discs is varied by means of a solenoid, the pressure on the pile being a function of the pull of the solenoid.

An object of my invention is to provide a regulator of the above-indicated character which is rapid in its action and is provided with means for preventing the regulator from hunting.

In the drawing, Figure 1 is a view in side elevation of a preferred form of my invention;

Fig. 2 is a view in end elevation of the regulator;

Fig. 3 is a diagrammatic view of the regulator connected to control the voltage of a dynamo electric machine, and,

Fig. 4 is a diagrammatic view of a modified form of regulator constructed in accordance with my invention.

Referring to Figs. 1, 2 and 3 of the drawings, an electromagnet is provided having a coil winding 1 and a movable core or armature member 2, which is actuated in accordance with the energization of the winding to control the action of the regulator. The core member 2 is pivotally connected at the point 3 to one arm 4 of a bell crank lever that is mounted to move about the pivot 5. The other arm of the bell crank lever 6 is adapted to vary the pressure applied to the carbon pile 7 in accordance with the movement of the lever. A biasing member 8 is provided to actuate the arm 6 of the bell crank lever to apply pressure to the carbon pile. The core member 2 of the electromagnet is connected to a dash-pot 9 through a resilient or

spring connection 11, which is biased in accordance with the movements of the core member 2 and biases the piston of the dash-pot in the one or the other direction.

As illustrated in Fig. 3 of the drawing, the regulator is connected to control the voltage of a generator 12 having an armature winding 13 and a field winding 14 that is connected in series circuit relation with the pile of carbon wafers 7. The terminals of the generator are connected to supply conductors 15 and 16, between which the coil 1 of the regulator magnet is connected.

Referring particularly to Figs. 1 and 2 of the drawing, the coil member 1 and the dash-pot 9 are illustrated as being suitably mounted on an insulating panel 17. The core member 2 of the magnet is connected to a piston 18 of the dash-pot 9 by means of the spring 11 and a rod 19.

Two piles of graphite or carbon wafers 7 are provided, supported between brackets 21 and 22 by means of eight non-conducting rods 23. The pivot 5 supports the bell crank lever having arms 4 and 6 between two projections 24, extending from the bracket 22. The upwardly extending portion of the bell crank lever is provided with flat laterally extending projections 25 for engaging the ends of the graphite piles 7. One end of the biasing member 8 is attached to the upper end of the portion 6 of the bell crank lever and the other end of the biasing member is attached to the bracket 21 by means of an adjusting screw 26.

The operation of the regulator is as follows: When the generator 12 is started and while the voltage is building up to its normal value, the spring 8 is biased to exert a pressure on the graphite discs 7, reducing the resistance of the pile and thereby permitting a relatively high current to flow in the field winding 14 of the generator. As the voltage of the generator increases, the excitation of the winding 1 correspondingly increases, and the core 2 of the electromagnet is moved upwardly, thus actuating the bell crank lever to release the pressure on the pile 7.

When the value of voltage impressed upon the winding 1 causes the pull of the electro-

magnet to balance the pull of the spring member 8, a position of stability has been reached, corresponding to the normal voltage for which the regulator has been adjusted. If the voltage across the supply conductors 15, 16 increases or decreases with respect to the desired value, the core member 2 will be actuated upwardly or downwardly and decrease or increase, respectively, the pressure on the pile 7, thus varying the resistance in the circuit of the field winding 14 to correct the voltage of the generator 12.

As the core member 2 is actuated in the one or the other direction to correct for voltage variations of the generator, it is necessary to prevent over-travel of this member to prevent the correction in the voltage of the generator to vary beyond or "overshoot" its desired value. This is accomplished by means of the dash-pot 9 and the biasing connection between the piston of the dash-pot and the core member 2. The dash-pot 9 tends to retard the action of the core member. However, because of the connection of the biasing member 11 between the dash-pot piston and the core member 2, the core is permitted to immediately travel the greater part of the distance corresponding to the change in excitation of the coil 1, and, as the tension or compression on the biasing member increases, the dash-pot piston is actuated and gradually follows the movement of the core member. It follows that the action of the regulator, while prompt in its response to a change in the voltage impressed on the regulating coil, approaches its new position gradually. That is to say the first part of the movement of the core member 2 is rapid and the latter part of the movement is gradual.

The regulator illustrated in Fig. 4 of the drawing is similar in its general character to that illustrated in Figs. 1, 2 and 3. In this form of the invention, however, the biasing member 11 and dash-pot 9 are replaced by the biasing member 27 and the dash-pot 28 which are connected as illustrated in perspective in Fig. 4. A lever 29 is provided which is pivotally supported at point 30 and normally occupies a position in the plane of the arm 4 of the bell crank lever. One end of the lever 29 is pivotally connected at 31 to the piston of the dash-pot 28 and is adapted to move vertically with the dash-pot piston. The biasing member 27 is connected between the pivot point 31 of the lever 29 and the pivot point 3 of the bell crank lever.

The spring or biasing member 27 normally occupies a substantially horizontal position. As the core member 2 of the electromagnet is actuated upwardly or downwardly to operate the regulator, the end of the spring member 27 connected to the pivot 3 is correspondingly actuated and increases the tension on the spring member. The tension of the spring member 27 exerts a component of its force

upwardly or downwardly according to the direction of movement of the pivot point 3, and correspondingly biases the pivot point 31. The pivot point moves accordingly, decreasing the tension on the spring 27 and permitting it to again assume a substantially horizontal position.

Many modifications may be made in the circuits and apparatus from that disclosed in my application without departing from the spirit of my invention, and I do not wish to be limited other than by the scope of the appended claims.

I claim as my invention:

1. In a regulator of the carbon-pile type, a pile of current conducting wafers, a biasing member for normally compressing said wafers, an electromagnet for releasing the pressure of said biasing member in accordance with the energization thereof, and anti-hunting means comprising a retarding element resiliently connected to said magnet for permitting movement of the magnet core in either direction prior to movement of the retarding element.

2. In a regulator of the carbon-pile type, a pile of current conducting wafers, a biasing member for normally compressing said wafers, an electromagnet for releasing the pressure of said biasing member in accordance with the energization thereof, and anti-hunting means comprising a retarding element, said retarding element being connected to said electromagnet through a resilient biasing member whereby a movement of the magnet takes place in either direction prior to a corresponding movement of the retarding element.

3. In a regulator of the carbon-pile type, a pile of current conducting wafers, a biasing member for normally compressing said wafers, an electromagnet for releasing the pressure of said biasing member in accordance with the energization thereof, and anti-hunting means comprising means for biasing said magnet against varying the pressure on said wafers for a desired period after a change in the excitation of said electromagnet in either direction.

4. In a regulator, an electromagnet energized in accordance with the quantity to be regulated and comprising an armature member actuated thereby, anti-hunting means for said regulator comprising a retarding element for retarding the movement of said armature to prevent over-travel, and a biasing member connected between said retarding element and said armature through which movement of the armature in either direction biases said retarding element in a corresponding direction.

In testimony whereof, I have hereunto subscribed my name this 3rd day of December, 1927.

JOHN H. ASHBAUGH. 120
